UNITED STATES PATENT OFFICE

151,791

DESIGN FOR PRUNING SHEARS

Justin L. Smith, Watertown, Conn., assignor to
Seymour Smith & Son, Inc., Oakville, Conn., a
corporation of Connecticut

Application September 2, 1947, Serial No. 141,155

Term of patent 14 years

(Cl. D22—5)

To all whom it may concern:

Be it known that I, Justin L. Smith, a citizen of the United States, residing in Watertown, county of Litchfield, and State of Connecticut, have invented a new, original, and ornamental Design for Pruning Shears, of which the following is a specification, reference being had to the accompanying drawing, forming part thereof.

Fig. 1 is a side view of the pruning shears, showing my new design.

Fig. 2 is a top view of the same.

Fig. 3 is a bottom view of the same.

Fig. 4 is an end view of the same.

I claim:

The ornamental design for pruning shears, as shown.

JUSTIN L. SMITH.
